STRAW-BRAID SEWING MACHINE

Rudolph Becker, North Plainfield, N. J., assignor
to The Singer Manufacturing Company, Elizabeth, N. J., a corporation of New Jersey

Application June 24, 1936, Serial No. 86,903

7 Claims. (Cl. 112—23)

This invention relates to sewing machines, more particularly of the type adapted to sew straw braid in the formation of hats, and has for an object to reorganize the mechanisms of the machines disclosed in U. S. Patents No. 1,429,399, dated Sept. 19, 1922, and No. 2,034,706, dated Mar. 24, 1936, so that the operator is not obliged, in lifting the presser-foot for the removal and insertion of work, to lift the looper-supporting slide-frame against a heavy spring-pressure such as heretofore used to resist displacement of the slide-frame and parts of the needle-stroke-varying mechanism connected with it, under operative stresses set up in the running of the machine.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

Referring to the accompanying drawings, Fig. 1 is a front side elevation, partly in section, of a sewing machine embodying the invention. Fig. 2 is a fragmentary front end elevation of the machine. Fig. 3 is a similar view with the presser-foot and looper-supporting slide-frame raised for the removal and insertion of work. Fig. 4 is a horizontal section through the machine bed showing parts of the needle-bar-actuating mechanism in plan. Fig. 5 is a vertical transverse section through the bracket-arm of the machine adjacent the looper-supporting slide-frame and presser-bar. Fig. 6 is a perspective view of the presser-foot and bar. Fig. 7 is a section approximately on the line 7—7, Fig. 1. Fig. 8 is a fragmentary view similar to Fig. 7, showing the relative movement between two yieldingly connected parts of the looper-supporting slide-frame positioning means, when the presser-foot is lifted to the position shown in Fig. 3. Fig. 9 is a section on the line 9—9, Fig. 7. Fig. 10 is a section on the line 10—10, Fig. 7. Fig. 11 is a rear elevation of the anchorage for the presser-bar spring, and Fig. 12 is a section on the line 12—12, Fig. 4.

The machine, except as hereinafter described, is constructed substantially in accordance with the disclosure of said U. S. Patent No. 2,034,706. It has a frame including the bed 1 and standard 2 of the overhanging bracket-arm 3 terminating in the head 4. Journalized in the bed 1 is the main shaft 5 having the needle-bar driving ball-

crank 6 which is connected by the pitman 7 to the ball 8 at the rear end of the cylindrical rod or lever 9 slidably mounted in the fulcrum guide-sleeve 10 the central portion 11 of which is of cubical form and has projecting from its lateral faces the aligned pivot-studs 12 journaled in the slide-blocks 13 which work in the guideways 14 in the bed 1. The slide-blocks 13 contact the side faces of the cubical central portion 11 of the fulcrum-sleeve 10 and are held on the pivot-pins 10 5 by the cap-screws 15.

At its forked forward end the lever 9 is connected by the pivot-pin 16 to the lower end of the elbow-shaped arm 17 rigid with the needle-bar 18 which is mounted for vertical reciprocation in the guideway 19 in the bed 1. The needle-bar 18 carries the usual hook-needle 20 and eye-pointed needle 21 arranged in side-by-side relation in the holder 22 fixed to the needle-bar. The lever 9 has fixed to it, adjacent its opposite ends, the guide-blocks 23 which work in vertical guideways between the guide-bars 24.

It will be understood that the length of the stroke imparted to the needle-bar 18 by the crank 6 will depend upon the position of the fulcrum-studs 12 and their bearing blocks 13 in the guideways 14. Further, it will be observed in Fig. 1, that when the crank 6 is at its highest point and the needle-bar 18 is at the lower limit of its stroke, the lever 9 is in parallelism with the guideways 14 which are inclined downwardly from their rearward ends toward the pivot 16. Hence adjustment of the fulcrum block 11 changes only the upper limit of the needle-stroke. This adjustment is made to suit the thickness of work to be sewn; the thicker the work, the longer is the required needle-stroke.

One of the guide-blocks 13, Figs. 1, 4 and 12, is connected by a stud-screw 25 and link 26 to an arm 27 extending upwardly from a collar 28 rotatably supported on the stud-pin 29 fixed in the bed 1 by the set-screw 30. Diametrically keyed at 31 to the collar 28 is the hub 32 of a hand-operated adjusting lever 33 carrying a spring-pressed locking-pin 34 receivable in any one of a series of locking apertures 35 in the plate 36 which is screwed to the machine frame. It will be understood that the operator may, at a moment's notice, shift the needle-bar fulcrum block 11 to any desired position and lock it in such position, by manipulation of the hand-lever 33. The fulcrum-block 11 is thus positively locked in adjusted position against displacement by any reactionary forces to which it may be subjected under high speed operating conditions.

Cooperating with the needles 20, 21, in the usual manner, are the loop-taking means or loopers 37, 38 which are carried by the slide-frame 39 movable vertically in the head 4. The looper 37, which seizes a thread-loop from the eye-pointed needle 21 and moves in a plane at one side of and parallel to the plane of the needles, is mounted on the looper-lever 40 which is fulcrumed at 41 in the slide-frame 39. The looper 38, which carries one limb of the seized thread-loop into the barb of the hook-needle 20, is mounted on the looper-carrier 42 which rocks on the pintles 43 and receives motion from the looper-lever 40 through the link-connection 44, all as disclosed in said United States Patent No. 2,034,706. The looper-mechanism is actuated by the usual crank-arm 45 on the rock-shaft 46 within the bracket-arm 3; the crank-arm 45 being pivotally connected at its lower end to a slide-block 47 embracing the looper-lever 40.

According to the present improvement the looper-carrying slide-frame 39 is yieldingly connected to the manually adjustable means for varying and unyieldingly maintaining the length 25 of stroke of the needle-bar. The connection preferably comprises a ball-stud 48 which is mounted on the slide-frame 39 and is connected by the link 49 to the crank-arm 50 on the rock-shaft 51 journaled within and lengthwise of the bracket-arm 3. The rock-shaft 51 is formed at its rear end with an integral arm 52 having at its end a lateral extension 53 which extends over a lever 54 of adjustable length loosely fulcrumed on the rock-shaft 51. A grass-hopper spring 55 35 coiled about a screw 56 in the rock-shaft 51 has one of its legs anchored in a hole in the arm 52. The other leg of the spring underlaps the arm 54. This spring is comparatively weak, as it is only required to be strong enough to restore the 40 slide-frame 39 to its normal sewing position after having been displaced therefrom by the operator in raising the presser-foot for removal and insertion of work. The arm 54, which is of adjustable length, comprises two sections held together by the usual screw-and-slot expedient 57.

The arm 54 is connected at its free end to the upper end of the link 58 which at its lower end is connected to one arm 59 of a bell-crank lever fulcrumed on the fixed stud 60. The other arm 50 61 of the bell-crank lever is connected by the link 62 to the stud-screw 25 on the slide-block 13 to which the manually adjustable lever 33 is connected.

It will be understood from the foregoing that 55 when the manually operable lever 33 is shifted to and locked in a selected position of adjustment, the length of the needle-stroke will be determined by the position of the needle-lever fulcrum block 11 which, through the described 60 connections, also determines the operative or sewing elevation of the slide-frame 39 which carries the loopers.

Slidably mounted in the head 4, alongside the slide-frame 39, is the comparatively light weight 65 presser-bar 63 carrying the usual presser-foot 64 with which the usual feed-dog 65 cooperates to feed the work 66. The presser-bar 63 has rigidly secured thereto an arm 67 having at its free end a roller 68 in position to be engaged by the usual manually operated presser-bar-lifting 70 cam-lever 69. The arm 67 has an upstanding branch 70 which is apertured at 71, Fig. 6, to receive the free end of a cantilever spring 72 anchored at its rear end 73 in the internal frame 75 lug 74 and carrying a guide-block 75, Fig. 1,

having a non-threaded hole receiving the lower end of the presser-bar-spring adjusting screw 76. The light-weight presser-bar has a limited working movement unaccompanied by movement of the heavier slide-frame 39 but has a shoulder 77 which engages and lifts the slide-frame when the cam-lever 69 is operated to raise the presser-bar for removal and insertion of work. The comparatively light spring 72 exerts only enough downward pressure upon the light-weight presser-bar 63 to properly hold the work for the feeding action of the feed-dog 65 which works as usual through an aperture in the work-support 65'.

The manually operated adjusting lever 33 is preferably so set that during the sewing of work of a given thickness, the presser-bar shoulder 77 does not engage and lift the slide-frame 39. The yielding connection (spring 55) between the slide-frame 39 and the locked adjusting lever 33, permits the slide-frame to rise when the lifting lever 69 is manipulated for removal and insertion of work. The strong slide-frame springs of U. S. Patents Nos. 1,429,399 and 2,034,706, heretofore, used to resist displacement of the slide-frame under operative stresses set up in the running of the machine, are thus eliminated and the operator is not obliged to overcome the resistance of a strong spring in lifting the presser-bar.

The invention is not to be understood as limited to the details of construction and relative arrangements of parts shown and described, as the drawings and foregoing description are merely a disclosure of one embodiment of the invention. Various modifications may obviously be made by those skilled in the art within the scope and spirit of the invention.

Having thus set forth the nature of the invention, what I claim herein is:—

1. A sewing machine having a reciprocating needle, means to reciprocate said needle including a manually adjustable needle-stroke-varying element and unyielding means to prevent displacement of said element from its adjusted position under operative stresses set up in running the machine, a loop-taker cooperating with said needle to form stitches, a loop-taker support, and positioning means for said loop-taker support yieldingly connected to said needle-stroke-varying element.

2. A sewing machine having reciprocating hook and eye-pointed needles, manually operated means to select and unyieldingly maintain a desired length of stroke of said needles to suit the thickness of work to be stitched, a movable looper-support yieldingly connected to said means, one or more loopers carried by said looper-support, and means to move said looper-support for removal and insertion of work.

3. A sewing machine having reciprocating hook and eye-pointed needles, manually operated means to adjust and unyieldingly maintain the length of needle-stroke to suit the thickness of work to be stitched, looper means cooperating with said needles to form stitches, a movable support for said looper means, a yielding connection between said looper support and said needle-stroke adjusting means, to position said looper support for cooperation of said looper means with said needles, a feed-dog, a presser-foot, a spring-pressed presser-bar movable independently of said looper support, and manually operated means to lift said presser-bar and looper support for removal and insertion of work.

4. A sewing machine having, in combination, a work-support, reciprocating hook and eye-

pointed needles mounted below the work-support, manually operated means to adjust the length of stroke of said needles, loop-taking means cooperating with said needles above the work-support, 5 a slide-frame carrying said loop-taking means, a feed-dog, a presser-foot, a spring-pressed presser-bar carrying said presser-foot, means on said presser-bar to lift said slide-frame when the presser-bar is raised for removal and insertion of work, and a yielding slide-frame-positioning connection between said slide-frame and the needle-stroke adjusting means.

5. A sewing machine having a reciprocating needle, a needle-operating lever, a shiftable fulcrum for said lever, manually operated means to adjust the position of said fulcrum and lock it in adjusted position, a looper-support yieldingly connected to said fulcrum adjusting means, and a looper carried by said looper support.

20 6. A straw-braid-sewing machine having a frame formed with a bed and an overhanging bracket-arm, a work-support on said bed, reciprocating hook and eye-pointed needles mounted in said bed, means in said bed to reciprocate 25 said needles, a manually adjustable lever on said

bed and connections therewith for varying the upper limit of the needle-stroke, a vertically movable looper-support mounted in said bracket-arm, loopers carried by said looper-support, yielding means interconnecting said needle-stroke-varying means with said looper-support to yieldingly position said looper-support for cooperation of said loopers with said needles, a feed-dog, a spring-pressed presser-foot movable vertically independently of the looper-support while the machine is sewing, and means to lift said presser-foot and looper-support for removal and insertion of work.

7. A straw-braid-sewing machine having a frame including a bed and a bracket-arm, reciprocating hook and eye-pointed needles mounted in said bed, a movable looper support mounted in said bracket-arm, loopers carried by said looper-support, a manually operated lever on said bed and connections to simultaneously adjust the length of stroke of said needles and the working elevation of said loopers, and means to lock said lever in adjusted position.

RUDOLPH BECKER. 25
